(57) **CLAIM**

The ornamental design for a polymer-based flooring, as shown and described.

DESCRIPTION

FIG. 1 is a perspective view of a polymer-based flooring showing our design;

FIG. 2 is a top view thereof;

FIG. 3 is a bottom view thereof;

FIG. 4 is a first side view thereof;

FIG. 5 is a second side view thereof;

FIG. 6 is a cross section view taken along lines 6-6 of FIG. 2;

FIG. 7 is a front view thereof; and,

FIG. 8 is a back view thereof.

The even-length broken lines are directed to environment, represent unclaimed subject matter, and form no part of the claimed design.

The long-and-short broken lines form an unclaimed boundary, and form no part of the claim.
